UNITED STATES PATENT OFFICE.

GEORGE W. HUGHEY, OF SPRINGFIELD, MISSOURI.

WRENCH.

1,195,020.

Specification of Letters Patent. Patented Aug. 15, 1916.

Application filed November 30, 1915. Serial No. 64,322.

To all whom it may concern:

Be it known that I, GEORGE W. HUGHEY, a citizen of the United States, residing at Springfield, in the county of Greene and State of Missouri, have invented new and useful Improvements in Wrenches, of which the following is a specification.

This invention relates to wrenches, and one of the objects thereof is to provide a simple, cheap and efficient device capable of rapid and reliable adjustment.

Another object of the invention is to construct a wrench with a rigid jaw having a longitudinally slotted shank, to arrange a 15 slidable jaw upon the shank, and to provide the slidable jaw with a pivoted hinged locking part which may be swung to frictionally engage with the inner edges of the bifurcated portion of the wrench and to 20 positively lock the jaw upon the shank.

With the above and other objects in view, the improvement resides in the construction, combination and arrangement of parts set forth in the following specification and falling 25 within the scope of the appended claims.

In the drawings: Figure 1 is a view in side elevation of a wrench constructed in accordance with the present invention, Fig. 2 is a central longitudinal sectional view 30 through the same, Fig. 3 is a transverse section through the sliding jaw, Fig. 4 is a similar section taken through the shank and through the locking block of the sliding jaw, Fig. 5 is a perspective view of the sliding jaw, Fig. 6 is a similar view of the locking block.

The wrench, in the form shown in Figs. 1 to 6, has its shank 1 provided with a laterally extending head 2 forming the same 40 with jaws disposed one to each of the opposite sides of the shank, and one of the said jaws preferably has its working face toothed, as indicated by the numeral 3.

The shank 1 is slotted longitudinally, providing the same with a pair of spaced bars 4-4, and the inner edges of these bars are provided with teeth 5.

The numeral 6 designates a handle which is removably secured to the reduced end of 50 the shank, and the removal of this handle permits of the arrangement on the said shank of a slidable jaw 7. The slidable member 7 comprises a head member having spaced slots or passages 8-8 through which 55 bars 4-4 of the shank 1 pass, and the said member is provided at the opposite sides of

the mentioned jaws with heads which are adapted to co-act with the jaws provided by the head 2. One of these jaws has transverse teeth 9 which are adapted to co-act 60 with the toothed jaw 3 of the head 2.

The end of the member 7 opposite that provided with the jaws is centrally formed with a lug 10 which is adapted to be received between spaced ears 11-11 provided upon a 65 locking block 12.

The numeral 13 designates a pintle which passes through the ears 11 and the lug 10 whereby the block 12 is hingedly secured to the sliding member 7. The block 12 has its 70 sides provided with teeth 14 which are adapted to engage with the teeth 5 of the arms 4 of the shank 1, when the block is swung between the said arms. In this connection it should be stated that the teeth of 75 the bars as well as the teeth of the block are arranged at a curve, so that the said block may be swung to either side of the shank 1 when the member 7 is to be slid upon the said shank. Also preferably the 80 space between the teeth, at the outer sides or faces of the members 4 is slightly widened to permit of the ready engagement of the teeth of the block between the teeth of the bars. 85

In order to retain the block between the bars 4 to hold the sliding jaw 7 in an adjusted position, I provide a catch member including a central portion or stem 15 which passes transversely through an opening in the 90 block and which has its ends provided with spring arms 16-16 which are of a width sufficient to be brought over the side or faces of either of the bars 4. The arms 16 are constructed preferably of spring material 95 and the ends of both are preferably flared outwardly and one of said ends is provided with a handle 17 whereby the catch may be readily actuated.

Having thus described the invention, what 100 I claim is:

1. A wrench having a rigid jaw provided with a longitudinally slotted shank, a sliding jaw carried by the shank, a swinging block carried by the jaw adapted to be 105 brought to engage with the inner edges of the slotted shank, and a pivoted latch carried by the block and adapted to be moved to engage with the slotted shank to hold the block in the slot of the shank. 110

2. A wrench having a rigid jaw provided with a longitudinally slotted shank forming

the same with spaced bars, the inner edges of which are toothed and the distance between the teeth is greater at the ends of the teeth than at the central portions of the 5 teeth, a sliding jaw carried by the wrench, a pivoted block on the jaw, said block having its edges toothed to engage with the teeth of the bars, a latch for the block comprising a member passing transversely through an 10 opening in the block and having its ends provided with spring arms of a length to engage with the shank at the opposite sides of its slots, and one of said spring arms being provided with a handle.

15 3. A wrench having a rigid jaw provided with a longitudinally slotted shank, the in-

ner edges of which are provided with rounded teeth and the distance between the teeth is greater at the ends thereof than at the central portion, a sliding jaw carried by the shank, a pivoted block for the jaw, said block having its ends formed with teeth to engage with the teeth of the slotted shank, and a latch member upon the block operable from either side thereof to lock the block 25 upon the shank.

In testimony whereof I affix my signature in presence of two witnesses.

GEORGE W. HUGHEY.

Witnesses:

CLARENCE E. HUGHEY,
XENIPHON HAWKINS.
